UNITED STATES PATENT OFFICE

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK

SLICING MACHINE

Application filed May 10, 1929. Serial No. 361,917.

My invention relates to a slicing machine and particularly to a slicing machine of the type in which a circular knife is rotated, for example by a motor, and the work to be sliced is conveyed across the face of the knife and past the cutting edge, for example upon a guided carriage. One object of my invention is to provide improved housing or enclosing means for the device, and particularly means for enclosing or housing the knife itself and the drive therefor. Another object is the provision of easily removable housing parts or members, whereby access may easily be had to the interior of the housing. Another object is the provision of an improved pusher plate, and particularly to means for permitting the pusher plate, and the work thereon, to be tilted out of operative position, for inspection of the work, without disengaging the work from the pusher plate. Other objects will appear from time to time in the course of the specification and claims.

I illustrate my invention more or less diagrammatically in the accompanying drawings, wherein—

Figure 1 is an elevation;

Figure 2 is a top plan view with parts broken away and parts in section;

Figure 3 is a section on the line 3—3 of Figure 1;

Figure 4 is a view of a housing guard plate;

Figure 5 is an end elevation of the pusher plate and associated parts; and

Figure 6 is a partial end view illustrating a housing guard plate.

Like parts are indicated by like symbols throughout the specification and drawings.

A generally indicates any suitable base member which may be provided, for example, with the yielding studs or ground engaging elements A¹, whereby the transmission of vibration is reduced.

B is any suitable housing member upwardly projecting from the base A. Associated with it is the motor housing B¹. The shaft B² of the motor, with the pulley B³ thereon, projects within the housing B and carries

50 the belt B⁴. B⁵ indicates a housing exten-

sion, associated with or forming part of the housing B which substantially covers the rear face of the knife, as shown in Figure 2, as by the apron B⁶. Mounted within it is the knife shaft B⁷ with the knife B⁸ thereon and the knife pulley B⁹ about which passes the belt B⁴.

C indicates a similar upward housing extension upon the opposite end of the slicing machine frame or base A. Mounted for movement in relation to the housing C is the gauge plate C¹ the position of which may be adjusted, through any suitable chain of gears or other mechanism, in response to rotation of the knob C². The details of the gauge plate and the adjusting means therefor do not of themselves form any part of the present invention and will not be considered in detail.

D indicates a cover member extending over the housings B and C and closing the upper portions thereof. It terminates about its edge in a flange D¹ which may rest on corresponding flanges D² on the two housings. Associated with the housings A and B are thickened upper portions D³ which may be penetrated for example by the securing screws D⁴ with their finger pieces D⁵ which pass through the top of the cover portion D. The sides of the cover are also shown as slotted as at D⁶, the purpose of these slots being considered below.

Closing the front of the housing B, and thus protecting and enclosing the major portion of the knife B⁸ is the guard plate generally indicated as E and shown in detail in Figure 4. This guard plate has an upper edge E¹ which penetrates, as shown in Figure 3 upwardly within the flange of the cover D. It is shown, as in Figure 4, as notched or slotted at E², E³, these notches being aligned with the slots D⁶ of the cover D. Aligned with them are adjusting abutments E⁴ which may for example be screw threaded into the members D³, and which in turn receive the screw threaded portions E⁵ of the securing members or screws E⁶, which exert, with the abutments E⁴, a clamping action on the upper edge of the guard plate E, at the slotted portions E².

- The plate E is further provided with the arcuate edge E⁶ which seats in the recessed front of the knife B⁸. The bottom of the plate E is also slotted, as at E⁷ E⁷, which slots may be aligned with adjustable abutments E⁸ which may be identical with those shown as at E³, and which receive the securing thumb screws E⁹, which may be substantially identical with the similar screws E⁵.
 5 The slots E⁷ are shown of such a size or length as to permit the plate E, when it is dropped to lowermost position, to clear the lower edge of the cover member D. E¹⁰ generally indicates a member, preferably fixed in relation to the frame B, in relation to which the abutments E⁸ may be adjusted, as by rotation. E¹¹ indicates any suitable scraper supported upon the plate E, its details forming no part of the present invention.
 10 G indicates a removable end closure plate for the housing B. It may for example be supported as by the screw G¹ which, when loosened, will permit the plate to be tilted or rotated. The lower end of the plate may be held as for example by the screw G² which passes through the slot G³.
 15 H H¹ indicate respectively a supporting and a guide track mounted upon the base A. Mounted thereon is the carriage member H² with its handle H³ and its downward projection H⁴, the adjustment members H⁵ H⁶ of which engage opposite sides of the guide track H¹. Mounted on the carriage H² is any suitable work supporting member generally indicated at H⁷ with a side flange H⁸ along the edge which is nearest to the knife when the carriage is withdrawn to the position in which it is shown in Figure 1. The flange H⁸ is herein shown as vertical and as lying in a plane perpendicular to the cutting plane of the knife. An important function of the flange H⁸ is to serve as a limit or positioning stop for the meat being cut.
 20 H¹ indicate respectively a supporting and a guide track mounted upon the base A. Mounted thereon is the carriage member H² with its handle H³ and its downward projection H⁴, the adjustment members H⁵ H⁶ of which engage opposite sides of the guide track H¹. Mounted on the carriage H² is any suitable work supporting member generally indicated at H⁷ with a side flange H⁸ along the edge which is nearest to the knife when the carriage is withdrawn to the position in which it is shown in Figure 1. The flange H⁸ is herein shown as vertical and as lying in a plane perpendicular to the cutting plane of the knife. An important function of the flange H⁸ is to serve as a limit or positioning stop for the meat being cut.
 25 H¹ indicate respectively a supporting and a guide track mounted upon the base A. Mounted thereon is the carriage member H² with its handle H³ and its downward projection H⁴, the adjustment members H⁵ H⁶ of which engage opposite sides of the guide track H¹. Mounted on the carriage H² is any suitable work supporting member generally indicated at H⁷ with a side flange H⁸ along the edge which is nearest to the knife when the carriage is withdrawn to the position in which it is shown in Figure 1. The flange H⁸ is herein shown as vertical and as lying in a plane perpendicular to the cutting plane of the knife. An important function of the flange H⁸ is to serve as a limit or positioning stop for the meat being cut.
 30 H¹ indicate respectively a supporting and a guide track mounted upon the base A. Mounted thereon is the carriage member H² with its handle H³ and its downward projection H⁴, the adjustment members H⁵ H⁶ of which engage opposite sides of the guide track H¹. Mounted on the carriage H² is any suitable work supporting member generally indicated at H⁷ with a side flange H⁸ along the edge which is nearest to the knife when the carriage is withdrawn to the position in which it is shown in Figure 1. The flange H⁸ is herein shown as vertical and as lying in a plane perpendicular to the cutting plane of the knife. An important function of the flange H⁸ is to serve as a limit or positioning stop for the meat being cut.
 35 H¹ indicate respectively a supporting and a guide track mounted upon the base A. Mounted thereon is the carriage member H² with its handle H³ and its downward projection H⁴, the adjustment members H⁵ H⁶ of which engage opposite sides of the guide track H¹. Mounted on the carriage H² is any suitable work supporting member generally indicated at H⁷ with a side flange H⁸ along the edge which is nearest to the knife when the carriage is withdrawn to the position in which it is shown in Figure 1. The flange H⁸ is herein shown as vertical and as lying in a plane perpendicular to the cutting plane of the knife. An important function of the flange H⁸ is to serve as a limit or positioning stop for the meat being cut.
 40 H¹ indicate respectively a supporting and a guide track mounted upon the base A. Mounted thereon is the carriage member H² with its handle H³ and its downward projection H⁴, the adjustment members H⁵ H⁶ of which engage opposite sides of the guide track H¹. Mounted on the carriage H² is any suitable work supporting member generally indicated at H⁷ with a side flange H⁸ along the edge which is nearest to the knife when the carriage is withdrawn to the position in which it is shown in Figure 1. The flange H⁸ is herein shown as vertical and as lying in a plane perpendicular to the cutting plane of the knife. An important function of the flange H⁸ is to serve as a limit or positioning stop for the meat being cut.
 45 H¹ indicate respectively a supporting and a guide track mounted upon the base A. Mounted thereon is the carriage member H² with its handle H³ and its downward projection H⁴, the adjustment members H⁵ H⁶ of which engage opposite sides of the guide track H¹. Mounted on the carriage H² is any suitable work supporting member generally indicated at H⁷ with a side flange H⁸ along the edge which is nearest to the knife when the carriage is withdrawn to the position in which it is shown in Figure 1. The flange H⁸ is herein shown as vertical and as lying in a plane perpendicular to the cutting plane of the knife. An important function of the flange H⁸ is to serve as a limit or positioning stop for the meat being cut.
 50 H¹ indicate respectively a supporting and a guide track mounted upon the base A. Mounted thereon is the carriage member H² with its handle H³ and its downward projection H⁴, the adjustment members H⁵ H⁶ of which engage opposite sides of the guide track H¹. Mounted on the carriage H² is any suitable work supporting member generally indicated at H⁷ with a side flange H⁸ along the edge which is nearest to the knife when the carriage is withdrawn to the position in which it is shown in Figure 1. The flange H⁸ is herein shown as vertical and as lying in a plane perpendicular to the cutting plane of the knife. An important function of the flange H⁸ is to serve as a limit or positioning stop for the meat being cut.
 55 H¹ indicate respectively a supporting and a guide track mounted upon the base A. Mounted thereon is the carriage member H² with its handle H³ and its downward projection H⁴, the adjustment members H⁵ H⁶ of which engage opposite sides of the guide track H¹. Mounted on the carriage H² is any suitable work supporting member generally indicated at H⁷ with a side flange H⁸ along the edge which is nearest to the knife when the carriage is withdrawn to the position in which it is shown in Figure 1. The flange H⁸ is herein shown as vertical and as lying in a plane perpendicular to the cutting plane of the knife. An important function of the flange H⁸ is to serve as a limit or positioning stop for the meat being cut.
 60 H¹ indicate respectively a supporting and a guide track mounted upon the base A. Mounted thereon is the carriage member H² with its handle H³ and its downward projection H⁴, the adjustment members H⁵ H⁶ of which engage opposite sides of the guide track H¹. Mounted on the carriage H² is any suitable work supporting member generally indicated at H⁷ with a side flange H⁸ along the edge which is nearest to the knife when the carriage is withdrawn to the position in which it is shown in Figure 1. The flange H⁸ is herein shown as vertical and as lying in a plane perpendicular to the cutting plane of the knife. An important function of the flange H⁸ is to serve as a limit or positioning stop for the meat being cut.
 65 H¹ indicate respectively a supporting and a guide track mounted upon the base A. Mounted thereon is the carriage member H² with its handle H³ and its downward projection H⁴, the adjustment members H⁵ H⁶ of which engage opposite sides of the guide track H¹. Mounted on the carriage H² is any suitable work supporting member generally indicated at H⁷ with a side flange H⁸ along the edge which is nearest to the knife when the carriage is withdrawn to the position in which it is shown in Figure 1. The flange H⁸ is herein shown as vertical and as lying in a plane perpendicular to the cutting plane of the knife. An important function of the flange H⁸ is to serve as a limit or positioning stop for the meat being cut.

J¹¹ J¹³ are in the position shown in full line in Figure 5 the plate J⁷ is vertical. When the handle J¹⁶ is upwardly lifted, the plate J⁷ is tilted into the dotted line position.

In order to limit the movement of the arms J¹¹ J¹³ I provide limit stops J¹⁷ J¹⁷ which abut against corresponding limit stops J¹⁸ upon the yoke J⁵.

Note that by positioning the axis of rotation of the plate J⁷ adjacent one edge, for example its lower edge, I permit it to be swung out of position without thrusting any portion of the work more closely against the gauge plate, as would be the case if the pivot point were intermediate the edges of the plate J⁷.

It will be realized that whereas I have described and shown a practical and operative device, nevertheless many changes might be made in the size, shape, number and disposition of parts without departing from the spirit of my invention. I therefore wish my description and drawings to be taken as in a broad sense illustrative and diagrammatic rather than as limiting me to my specific showing. The use and operation of my invention are as follows:

In slicing machines of the type herein disclosed, in which a sharp circular knife is rotated at high speed by a motor it is important that the interior of the housing be protected so far as possible from bits of meat and the like which adhere to the knife. When the knife is used on fatty substances, such as ham or bacon, its high rate of speed creates by friction sufficient heat to cause larding or the deposit of lard or grease on the knife. The scraper E¹¹ is instrumental in removing from the blade at least a substantial proportion of the material it so adheres. However, inevitably material does pass within the housing and where the device is used on heavy duty, as in packing houses, where it may be in almost continuous operation, access to the interior of the housing becomes important. This is true not only to permit cleaning, but to give access to the belt, grinding means and the like. I have therefore developed a device which gives a high degree of protection or enclosure, but which is nevertheless susceptible of easy access. Thus the cover member D may be quickly removed, by the rotation and removal of the securing screws D⁵, which are so formed as to be easily rotated by the fingers. The cover may be lifted off without interfering with the position of the guard plates. On the other hand the guard plates may be easily removed without interfering with the position of the cover. Thus if the securing screws E⁵ are loosened and then the securing screws E⁹ the plate E may drop or be lowered until the inner ends of the notches E⁷ rest on the screws E⁹. When in such position its upper edge clears the depending flange of the cover D and the plate

may be swung into the dotted position in which it is shown in Figure 3 and lifted from the screws E^9 and removed. It may be reinserted in the same way and the whole operation, the removal and reinsertion may be accomplished in a few seconds. Similarly the end plate G may be swung in an instant into the open position, to permit access to the end of the housing.

10 Mounted upon the work supporting member H^7 I have illustrated a follower or pusher or face plate which is particularly adaptable for use in slicing or reducing operations in which one substance is being trimmed off of another. For example in cutting certain pieces of meat in packing house products it may be desirable to trim off all fat from a lean piece or all the lean from a fat piece. The operator, in such case, cannot determine 20 whether or not he has completed his operation, without inspecting the face of the work. Or at least, he can do it much more rapidly and with a minimum of waste, by inspecting the face of the work. For this reason I provide a plate which can be used to thrust the meat against the gauge plate or back plate C^1 but which may be swung, for example, about a horizontal axis, without detaching the work from it, to permit the operator to 30 inspect the face of the work. Hence the links J^{11} J^{12} which normally hold the plate J^7 in the vertical full line position in which it is shown in Figure 5. An upward lift on the handle J^{16} permits the operator to 35 inspect the condition of the face of the work. When he again depresses the handle J^{16} the work plate J^7 may be returned exactly to the position in which they were prior to the inspection, with the work abutting against 40 the gauge or back plate and the carriage may then be reciprocated past the cutting edge for a further cutting stroke, if such stroke is still necessary.

I claim:

45 1. In a slicing machine, a base, a supporting structure upwardly extending therefrom, a rotary knife mounted upon said supporting structure, the supporting structure substantially enclosing the rear of the knife, a guard plate, a cover member overlying the supporting structure and surrounding the upper edge of the guard plate when the guard plate is in operative position, said guard plate being provided adjacent its lower edge with 50 securing apertures, securing members penetrating said apertures and adapted to hold the guard plate fixed against movement in relation to the supporting structure, the apertures being of such size as to permit the upper edge 55 of the guard plate to clear the cover member when the securing members are loosened, and the guard plate drops for the full height of 60 the apertures.

65 2. In a slicing machine including a rotary knife and means for rotating it and a sup-

porting structure upon which the knife is mounted, a guard plate overlying the forward face of the knife, said guard plate being provided with vertical slots at top and bottom, in communication with the upper and lower edges of said guard plate, and securing members aligned with said slots and adapted to hold said guard plate normally fixed in relation to said supporting structure.

3. In a slicing machine including a rotary 75 knife and means for rotating it and a supporting structure upon which the knife is mounted, a guard plate overlying the forward face of the knife, said guard plate being provided with vertical slots at the bottom, in communication with the lower edge of said guard plate, and securing members aligned with said slots and adapted to hold said guard plate normally fixed in relation to said supporting structure.

4. In a slicing machine including a rotary 80 knife and means for rotating it and a supporting structure upon which the knife is mounted, a guard plate overlying the forward face of the knife, said guard plate being provided with vertical slots at the bottom, in communication with the lower edge of said guard plate, and securing members aligned with said slots and adapted to hold said guard plate normally fixed in relation to said supporting structure. 85

130

5. In a slicing machine including a rotary knife and means for rotating it, and a supporting structure upon which the knife is mounted, a housing portion associated with said supporting structure and substantially shielding the rear of the knife, a guard plate secured to said housing portion, overlying the forward face of the knife, a cover member overlying the upper portions of the supporting structure and the guard plate and enclosing the space therebetween, and an end plate removably mounted upon the supporting structure and adapted, when removed, to give access to the space between supporting structure and guard plate.

6. In a slicing machine including a rotary 115 knife and means for rotating it, and a supporting structure upon which the knife is mounted, a housing portion associated with said supporting structure and substantially shielding the rear of the knife, a guard plate secured to said housing portion, overlying the forward face of the knife, a cover member overlying the upper portions of the supporting structure and the guard plate and surrounding the upper edge of the guard plate,

120 said guard plate being removable independently of the position of said cover member,

when the cover member is in normal operative position.

7. In a slicing machine including a rotary knife and means for rotating it, and a supporting structure upon which the knife is mounted, a housing portion associated with said supporting structure and substantially shielding the rear of the knife, a guard plate secured to said housing portion, overlying the forward face of the knife, a cover member normally overlying the upper portions of the supporting structure and the guard plate and surrounding the upper edge of the guard plate, means for normally maintaining the guard plate in position with its upper edge within the cover member, said means being adapted, when unloosed, to permit the guard plate to drop sufficiently to permit the upper edge of the guard plate to clear the lower edge of the cover member.

8. In a slicing machine including a rotary knife and a work supporting carriage, a pusher plate and a support therefor, the pusher plate being pivoted to said support, guiding means for guiding support and pusher plate for movement toward and away from the cutting plane of the knife, said guiding means including a sleeve mounted upon the carriage and a member slidably in said sleeve, and a linkage connection between said slidable member and said pusher plate, in engagement with said pusher plate at a point spaced away from the axis of rotation of the pusher plate.

9. In a slicing machine including a rotary knife and a work supporting carriage, a pusher plate mounted on said carriage for movement toward and away from the cutting plane of the knife, said pusher plate being pivoted in relation to said carriage, for rotation about a horizontal axis parallel with the cutting plane, and means for rotating said pusher plate about its pivot, including a linkage connection between the pusher plate and the carriage.

10. In a slicing machine including a rotary knife and a work supporting carriage, a pusher plate mounted on said carriage for movement toward and away from the cutting plane of the knife, said pusher plate being pivoted in relation to said carriage, for rotation about a horizontal axis parallel with the cutting plane, and means for rotating said pusher plate about its pivot, including a linkage connection between the pusher plate and the carriage, the pusher plate being mounted for rotation about an axis below the level of the connection between the pusher plate and the linkage.

11. In a slicing machine including a rotary knife and a carriage and means for guiding said carriage for movement across the face and past the cutting edge of the knife, a work supporting member mounted on said carriage and adapted directly to underlie and support

the work during movement of said work across said supporting member and toward the cutting plane, a pusher plate adapted to engage the work, a support for said pusher plate, spaced away from the effective supporting surface of said supporting member, and a pivotal connection between said support and said pusher plate, the axis of said pivotal connection being horizontal and parallel with the cutting plane.

12. In a slicing machine including a rotary knife and a carriage and means for guiding said carriage for movement across the face and past the cutting edge of the knife, a work supporting member mounted on said carriage and adapted directly to underlie and support the work during movement of said work across said supporting member and toward the cutting plane, a pusher plate adapted to engage the work, a support for said pusher plate, spaced away from the effective supporting surface of said supporting member, and a generally horizontal pivotal connection between said support and said pusher plate, the axis of said pivotal connection being parallel with the cutting plane.

13. In a slicing machine including a rotary knife and a carriage and means for guiding said carriage for movement across the face and past the cutting edge of the knife, a work supporting member mounted on said carriage and adapted directly to underlie and support the work during movement of said work across said supporting member and toward the cutting plane, a pusher plate adapted to engage the work, a support for said pusher plate, spaced away from the effective supporting surface of said supporting member, and a pivotal connection between said support and said pusher plate, the axis of said pivotal connection being horizontal and parallel with the cutting plane, the lower edge of the pusher plate being out of contact with the surface of the supporting member.

14. In a slicing machine including a rotary knife and a carriage and means for guiding said carriage for movement across the face and past the cutting edge of the knife, a work supporting member mounted on said carriage and adapted directly to underlie and support the work during movement of said work across said supporting member and toward the cutting plane, a pusher plate adapted to engage the work, an arm on which said pusher plate is mounted, guiding means for said arm, spaced away from the effective supporting surface of the supporting member, and a pivotal connection between said arm and the pusher plate, the axis of said pivotal connection being horizontal and parallel with the cutting plane.

15. In a slicing machine which includes a knife and means for actuating it, a work supporting carriage and means for guiding it past the cutting edge of the knife, a pusher

plate support mounted upon said carriage, said support being spaced away from the effective work supporting portion of the carriage, a pusher plate mounted upon said pusher plate support, for movement toward and away from the cutting plane of the knife, and a tilting connection between said pusher plate and pusher plate support, adapted to permit said pusher plate to rotate about an axis generally parallel with the path of movement of the carriage.

16. In a slicing machine including a knife and a work supporting carriage, a manually operable pusher plate mounted on said carriage, for bodily movement toward and away from the cutting plane of the knife, and a support for said pusher plate, said pusher plate being pivoted to said support for rotation about a generally horizontal axis parallel with the cutting plane and adjacent the lower edge of the plate, and means effective positively to rotate said pusher plate about its axis.

Signed at Indianapolis, county of Marion and State of Indiana, this 6th day of May, 1929.

WILLIAM J. CAMPBELL.
